No. 846,753.

PATENTED MAR. 12, 1907.

J. A. MURPHY,
RAIL ANCHOR.
APPLICATION FILED DEC. 29, 1906.

UNITED STATES PATENT OFFICE.

JOHN A. MURPHY, OF WHITE HAVEN, PENNSYLVANIA.

RAIL-ANCHOR.

NO. 846,753.

Specification of Letters Patent.

Patented March 12, 1907.

Application filed December 29, 1906, Serial No. 350,026.

To all whom it may concern:

Be it known that I, JOHN A. MURPHY, a citizen of the United States, residing at White Haven, in the county of Luzerne and State of Pennsylvania, have invented a new and useful Rail-Anchor, of which the following is a specification.

Considerable difficulty is experienced in railroad-track construction, especially on heavy or steep grades and at curves by the rails running or creeping. This is due in a measure to the expansion and contraction of the steel rails under temperature changes. Also the rails will run or creep with the trains passing over them and cause the track to kick or buckle out of line in hot weather. Consequently the track has to be frequently restored by a laborious operation. To prevent the running or creeping of the rails, devices known as "anchors" are employed.

The present invention relates to rail-anchors designed to overcome the objections above referred to, and it has for one of its objects to provide an anchor which is of simple and substantial construction and possessing great strength compared with its lightness and amount of material required in its construction.

A further object of the invention is the provision of a comparatively inexpensive rail-anchor which is adapted to be used in connection with rails of ordinary form without necessitating any changes in standard track constructions, the anchor being made in two parts and provided with means for firmly locking said parts in position on the rails, so that the anchor or anchors will engage the cross-ties and prevent the rails from creeping with respect to the latter.

With these objects in view and others, as will appear as the nature of the invention is better understood, the invention comprises the various novel features of construction and arrangement of parts which will be more fully described hereinafter, and set forth with particularity in the claims appended hereto.

In the accompanying drawing, which illustrates one of the embodiments of the invention, Figure 1 is a transverse section of the rail-anchor, showing the end of one of the rails and the shank of the fastening-bolt partly broken away. Fig. 2 is a perspective view of one section of the rail-supporter with a portion broken away. Fig. 3 is a side view of one section of the rail-supporter.

Corresponding parts in the several figures

are indicated throughout by similar characters of reference.

Referring to the drawing, A designates one of the rails of a railroad-track, which may be of any approved construction and comprising a head 1, a web 2, and a base 3.

The anchor or support B is composed of two longitudinally-divisible sections 4, which meet in a plane passing centrally through the web 2, and these sections are secured together under the base of the rail by the transversely-extending bolt 5. The sections 4 are metal castings each comprising a body composed of two vertically-disposed side walls or webs 6, connected together by flat vertical end walls or webs 6' in the form of a rectangle or square. The webs at the inner portions of the sections are somewhat larger than the outside vertical webs. The two vertical outside webs of the sections are provided with inwardly-extending flanges 7, that engage over the outer edges and top of the base 3 of the rail, so as to support the anchor on the latter. The four walls of the sections extending parallel with the length of the rail are provided with alining openings 8, through which the bolt 5 extends. By means of this bolt the two sections are drawn together inwardly with respect to the base 3 of the rails, and the bolt is located approximately under the point where the rails meet.

In order to increase the grip on the rail, the inner walls of the sections are provided with serrations 9 and the end walls with serrations 10, which serrations bite into the under side of the base 3. The outer walls have on their inner surfaces the serrations 11, which engage with the edges 12 of the base 3, and on the under surface of the inclined overhanging flanges 7 are the transversely-extending serrations 13, which engage the top surface of the base 3. By means of these serrations relative movement of the rail and anchor is positively prevented.

In practice the anchors are placed on the rails with their flat webs 6' bearing against the cross-ties, so that the rails cannot run or move without carrying the ties with them. In some cases, as on very heavy grades, five or six anchors are applied to each rail-section of the track. When the parts of the anchor are placed on the track, the inner webs 6 will not abut, and when the bolt 8 is drawn up tight the parts will be forced into contact at the lower edges of the inner webs, as shown in Fig. 1.

I have described the principle of operation of the invention, together with the construction which I now consider to be the best embodiment thereof; but I desire to have it understood that the device shown is merely illustrative and that various changes may be made when desired as are within the scope of the claim.

What is claimed is—

10 The combination of a rail, a two-part anchor therefor, each part comprising a pair of webs extending longitudinally with respect to the rail and arranged one under the web of the rail and the other adjacent the outer 15 edge of the rail-base, transversely-connect-

ing webs between the first-mentioned pair of webs, a flange extending inwardly from the top of the outer web to engage over the rail-base, and a bolt extending through the longitudinally-extending webs of the two parts 20 of the support, the inner longitudinal webs of the parts being of greater cross-sectional area than the outer webs.

In testimony that I claim the foregoing as my own I have hereto affixed my signature 25 in the presence of two witnesses.

JOHN A. MURPHY.
